COMBINED SPRING AND FRICTION SHOCK ABSORBER

**Stacy B. Haseltine, La Grange, Ill., assignor to
W. H. Miner, Inc., Chicago, Ill., a corporation
of Delaware**

Application May 13, 1943, Serial No. 486,804

6 Claims. (Cl. 267—9)

This invention relates to improvements in combined spring and friction shock absorbers, especially adapted for use in connection with railway car trucks.

One object of the invention is to provide a combined spring and friction shock absorber for railway car trucks including a cluster of springs together with a simple and efficient friction means for dampening or snubbing the action of the springs to minimize the vibrations imparted to the car body, thereby protecting the car and its lading against damage which would otherwise occur.

A more specific object of the invention is to provide in combination with the usual four spring cluster of a truck spring arrangement of railway cars, friction means for snubbing the action of the springs, comprising relatively slidable friction elements composed of two pairs of such elements held in frictional contact with each other by the expansive action of the truck spring members, the members of each pair being movable with the respective spring follower of the truck spring cluster, and the group of elements comprising the two pairs being accommodated in the space existing between the units of the spring cluster.

Other objects of the invention will more clearly appear from the description and claims herein-after following.

In the drawing forming a part of this specification, Figure 1 is a top plan view of a portion of a railway car truck illustrating my improvements in connection therewith. Figure 2 is a side elevational view of Figure 1, looking upwardly in said figure. Figure 3 is a horizontal sectional view, corresponding substantially to the line 3—3 of Figure 2. Figure 4 is a vertical sectional view, corresponding substantially to the line 4—4 of Figure 3. Figure 5 is a top plan view of the bottom spring follower of the device shown in Figure 4. Figure 6 is a transverse, vertical, sectional view, corresponding substantially to the line 6—6 of Figure 5. Figure 7 is a top plan view of one of the friction elements shown in Figure 4, looking downwardly in said last named figure. Figure 8 is a side elevational view of the friction element in Figure 7. Figure 9 is an elevational view of Figure 8, looking from right to left in said figure. Figure 10 is a broken view, similar to Figure 3, on an enlarged scale, showing the spring and friction unit, illustrating another embodiment of the invention. Figure 11 is a vertical sectional view, corresponding substantially to the line 11—11 of Figure 10.

In said drawing, 10 indicates one of the side

frame members of a railway car truck. The side frame 10, as shown, is in the form of a casting and has top and bottom members 11 and 12 connected by spaced vertical sections 13—13 forming guides for the truck bolster. As will be understood by those skilled in this art, the truck includes two side frame members 10—10, a truck bolster 14, a spring plank 15, and the usual truck springs. The opposite ends of the spring plank 15 are supported on the bottom members 12—12 of the truck side frames 10—10, and the opposite ends of the bolster 14 are guided between the sections 13—13 of the truck side frames. As shown most clearly in Figure 2, the sections 13—13 are inwardly offset near the upper ends to provide guides 16—16, which cooperate with guide seats 17—17 at the sides of the bolster 14. The springs at each side of the truck rest on the spring plank 15 and support the corresponding end of the bolster 14, thus yieldingly supporting the latter, which in turn supports the car body by means of the usual body bolster.

My improved combined spring and friction shock absorber is interposed between the truck bolster and spring plank of the car truck and forms a unit replacing the usual truck spring cluster.

Referring first to the embodiment of the invention illustrated in Figures 1 to 9 inclusive, my combined spring and friction shock absorber comprises broadly top and bottom spring plates A and B, four spring units C—C—C—C, and two pairs of friction elements D—D and D—D.

The top and bottom spring plates A and B are of similar design, except as hereinafter pointed out. Each spring plate is of substantially rectangular outline, having rounded corners, as shown most clearly in Figures 1 and 5. As shown in Figures 5 and 6, the spring plate B is provided with a pair of openings 18—18 therethrough which are at diagonally opposite sides of the center of the plate. Between the openings 18—18 the central portion of the plate is upwardly raised or offset to provide a strap portion 19. The openings 18—18 form seats to accommodate the base portions of the friction elements D—D of one of the pairs, as hereinafter more fully described. The spring plate A is provided with openings and a strap similar to the openings 18—18 and strap 19 of the plate B, but the plate A is in a position rotated through an angle of 90° to the plate B, so that the openings thereof are located on a diagonal line with respect to the plate B which is at right angles to the diagonal line of the openings of the latter. In

other words, the openings of the plate A alternate with the openings of the plate B. Each of the plates A and B is further provided with the usual inwardly projecting spring centering bosses 20-20. These bosses are four in number and are spaced symmetrically about the central vertical axis of the mechanism.

The spring units C-C-C-C preferably correspond in size and capacity to the units of the usual truck spring cluster of a railway car truck, and in actual practice the standard spring units of a four spring cluster are employed. Each spring unit C comprises a relatively heavy outer coil and a lighter inner coil, the coils being interposed between the spring plates A and B with the inner coil of the unit centered by the corresponding bosses 20-20 of the top and bottom plates A and B.

The four friction elements D-D-D-D are of like design, each being in the form of a casting comprising a postlike plate member 21 of broadly triangular, transverse cross section, having a laterally projecting base flange or foot 22 at one end thereof. On the inner side, the plate or post member 21 presents two flat friction surfaces 23-23 at right angles to each other. As will be seen upon reference to Figures 3, 4, 8, 9, and 10, the projecting base flange or foot member 22 extends from the side of the friction element opposite to the friction surfaces 23-23 thereof. The angle between the friction surfaces 23-23 and the bottom face of the foot member 22 is slightly in excess of a right angle, as clearly shown in Figures 4, 8, and 9, whereby said foot member is slightly inclined to the horizontal when the parts are assembled, thus providing for rocking lever action of the foot member on its support. The post or plate member 21 is cut away at the outer side, as indicated at 24, to clear the corresponding spring C of the spring units, as clearly shown in Figures 3 and 7, the cut away portion being transversely curved to correspond with the curvature of the outer coil of the corresponding spring unit C. At the base end of the post opposite to the foot member 22 is a laterally projecting retaining lug 25 adapted to engage in back of the strap 19 of the corresponding follower plate A or B.

The friction elements of the two pairs D-D and D-D are alternated and reversely arranged end for end with the friction surfaces 23-23 and 23-23 of one pair engaged face to face with the friction surfaces 23-23 and 23-23 of the other pair. In other words, the friction elements of one pair have the base flanges or foot members at the bottom of the mechanism and the other pair has the same at the top of the mechanism. The base members 22-22 of the one pair of friction elements D-D are seated respectively in the openings 18-18 of the bottom plate B, with the lugs 25-25 of said elements engaged underneath the strap 19 of said plate, and the base members 22-22 of the other pair of friction elements D-D are seated respectively in the openings 18-18 of the top plate A with the lugs 25-25 of said elements engaged behind the strap 19 of said plate. The shape of the base flanges or foot members is such as to fit the openings 18-18 and 18-18 of the plates A and B, but sufficient clearance is provided between each base foot member and the side and end walls of the seat to allow the foot to have relatively free rocking movement within the seat. The springs C-C-C-C overlap the base or foot members 22-22, two transversely opposite springs overlapping the base members 22-22 at the bot-

tom end of one pair of elements D-D and the remaining two transversely opposite springs overlapping the base members 22 at the top ends of the other pair of elements D-D. As will be evident the base members of the friction elements D-D-D-D are thus subjected to the pressure of the springs and the tendency is to rock the friction elements toward each other to press the friction surfaces thereof into tight frictional engagement.

The top and bottom spring plates A and B bear respectively on the underneath surface of the truck bolster 14 and the top of the spring plank 15. The base members 22-22 and 22-22 of the four friction elements D-D and D-D engage through the openings of the spring plates A and B and bear respectively on the bolster and spring plank. The friction elements D are thus held in tight frictional engagement with each other by the springs C-C due to the leverage action of the base members 22-22 and 22-22 which have rocking engagement at their outer ends with the cooperating faces of the truck bolster and spring plank.

The post or plate member 21 of each friction element D is of lesser height than the distance between the spring plates A and B at the time that the springs C-C-C-C are in the expanded position shown in Figure 4. The top ends of the lower friction elements D-D and the bottom ends of the upper friction elements D-D are thus normally spaced from the inner sides of the top and bottom spring plates A and B, respectively. The clearance thus provided is sufficient to permit of the required compression of the springs C-C-C-C in service. Engagement of the ends of the friction members D-D and D-D with the straps 19-19 of the respective plates serves to limit compression of the mechanism and prevents the springs from being unduly compressed.

The operation of my improved mechanism shown in Figures 1 to 9 inclusive is as follows: Upon relative approach of the spring plank and truck bolster, the coils of the group or cluster of springs C-C-C-C are compressed between the plates A and B. At the same time, the friction elements D-D and D-D are forced to slide relatively lengthwise on each other, being actuated respectively by the spring plank and bolster. A friction snubbing action is thus produced during compression of the springs. During recoil of the springs, the friction elements are returned to the normal position shown in Figures 2 and 4, the base members 22-22 and 22-22 of the friction elements being moved outwardly away from each other with the spring plates by the recoil of the springs. The recoil action of the springs is damped or snubbed by the friction elements D-D and D-D which are held in tight frictional engagement through the spring pressure acting on the rocking arm or base portions of the friction elements. As will be evident, as the springs are being compressed the frictional resistance produced by the relative movement of the elements D-D and D-D is augmented due to the increased pressure of the springs on the arms or base portions 22-22 and 22-22. As the springs recoil, the frictional resistance is progressively reduced due to the reduction of the spring pressure on the rocking friction elements.

Referring next to the embodiment of the invention illustrated in Figures 10 and 11, the improved combined spring and friction shock absorber is similar to the design described in con-

nection with Figures 1 to 9 inclusive with the exception that the friction elements thereof are of different design and the spring plates are accordingly modified to properly cooperate with these friction elements. The friction elements, which are indicated by E—E and E—E in Figures 10 and 11, have vertically disposed, platelike post portions 21—21 in sliding frictional engagement with each other, each post being of substantially the same transverse cross section as the post of the friction element D hereinbefore described and having flat friction surfaces 23—23 in sliding frictional engagement with the corresponding friction surfaces of the cooperating elements E—E. Each friction element has a laterally projecting base flange or foot portion 26 at one end thereof. The foot members or flanges 26—26 and 26—26 of the pairs of friction elements E—E—E are adapted to engage the bolster and spring plank of the truck of the car, respectively, and have their outer end sections inclined, respectively, away from the bolster and spring plank, as indicated in Figure 11, to provide for rocking action of the friction elements in a manner similar to the elements D—D—D—D, hereinbefore described.

The top and bottom spring follower plates employed with the friction elements E—E and E—E are similar to the plates A and B, except as hereinafter pointed out. The bottom spring follower plate which corresponds to the plate B, hereinbefore described, is indicated by F in Figures 10 and 11. The plate F has two openings on a diagonal line of the plate, at opposite sides of the center, as indicated at 27—27, and each boss of the plate, which is indicated by 28, is cut out at the inner side, as indicated at 29, the cut out portion forming a continuation of the corresponding opening 27. As shown in Figure 11, the foot members of the two bottom friction elements E—E are seated in the corresponding openings 27—27 with the outer end of the foot member of each element E extending through the cut out of the boss 28 in underlying relation to the boss, thereby anchoring the friction member to the plate. On the inner sides the bases of the elements E—E are notched, as indicated at 30—30, to clear the connecting portion between the openings 27—27 of the spring follower plate F. The top spring follower plate of the combined friction and spring shock absorbing means shown in Figures 10 and 11 is identical with the bottom plate F, and in the assembled device is in a position rotated through an angle of 90° to the plate F so that the openings thereof are in proper position to receive the foot members of the top friction elements E—E.

I have herein shown and described what I now consider the preferred manner of carrying out my invention, but the same is merely illustrative and I contemplate all changes and modifications that come within the scope of the claims appended hereto.

I claim:

1. In a shock absorber interposed between top and bottom, relatively movable members to yieldingly resist relative approach thereof, the combination with opposed spring plates bearing on said members respectively; of a pair of top friction elements; a pair of bottom friction elements, said top and bottom friction elements being alternated and in lengthwise sliding engagement with each other, each member of one pair engaging both members of the other pair, each element having a rocker base portion integral therewith,

said base portions extending through the plates respectively and having rocking engagement with said members; and springs interposed between and engaging said spring plates and overlapping said base portions of the friction elements to rock the latter into tight frictional engagement with each other.

2. In a shock absorber interposed between top and bottom, relatively movable members to yieldingly resist relative approach thereof, the combination with top and bottom pairs of friction elements, arranged in annular series, said top elements being alternated with said bottom elements, said top and bottom elements having longitudinal relative movement with respect to each other and being in frictional contact, said top elements having laterally projecting flanges at the upper ends integral therewith and in rocking engagement with said top member, said bottom elements having laterally projecting foot flanges at the lower ends integral therewith and in rocking engagement with said bottom member; of two sets of springs interposed between said members for opposing relative approach thereof, one of said sets of springs bearing on the flanges of said top elements, and the other set of springs bearing on the flanges of said bottom elements for pressing said elements into tight frictional engagement.

3. In a shock absorber interposed between two relatively movable members to yieldingly resist relative approach thereof, the combination with opposed spring plates bearing on said members respectively, each spring plate having openings therethrough and a retaining shoulder at one end of each opening; of two pairs of opposed, interengaging, relatively lengthwise slidable friction elements, the members of each pair having frictional engagement with both members of the other pair, said elements having laterally projecting base flanges rigid therewith, the base flange of one pair of said elements extending into the openings of one of said plates and having anchored engagement with the retaining shoulders thereof, the base flange of another of said elements extending into the openings of the other of said plates and having anchored engagement with the retaining shoulders thereof, said base flanges of said elements having pivotal engagement with said members respectively; and springs interposed between said members and bearing on said flanges of said elements for rocking the latter into tight frictional engagement.

4. In a shock absorber interposed between two relatively movable members to yieldingly resist relative approach thereof, the combination with a spring plate abutting each member, each plate having a projecting central retaining strap portion and a pair of openings therethrough, said openings being at opposite sides of and adjacent said strap portion; of a pair of friction elements having base flanges at one set of ends thereof seated in the openings of one of said plates; a second pair of friction elements alternated with said elements of the first named pair, and having lengthwise sliding frictional contact with said first named pair, said elements of the second pair having base flanges at one set of ends thereof seated in the openings of the other of said plates, each of said elements having a retaining lug thereon engaging the strap portion of the corresponding spring plate to anchor said element to the plate; and springs bearing at opposite ends on said spring plates and bearing on the base flanges of said elements.

5. In a shock absorber interposed between two relatively movable members to yieldingly resist relative approach thereof, the combination with a spring plate abutting each member, each plate having a pair of openings therethrough at opposite sides of the center of said plate and a raised retaining shoulder at the outer end of each opening; of a pair of friction elements having base flanges at one set of ends thereof seated in the openings of one of said plates and engaging in back of the shoulders of said plate to anchor said elements to the plate; a second pair of friction elements having lengthwise sliding frictional engagement with said first named pair, said second pair of elements having base flanges at one set of ends thereof seated in the openings of the other of said plates and engaging in back of the shoulders of said plate to anchor said elements to said plate; and springs bearing at opposite ends on said spring plates, said springs also bearing on the base flanges of said elements.

6. In a shock absorber interposed between top and bottom, relatively movable members to yieldingly resist relative approach thereof, the combination with top and bottom spring plates re-

5 spectively abutting said top and bottom members, each plate having four raised spring centering bosses thereon, said bosses being symmetrically disposed about the center of said plate, each plate having a pair of openings therethrough at opposite sides of the center of said plate, said openings being adjacent the inner sides of two diagonally located bosses of said plate; of a top pair of friction elements having base flanges at the upper ends thereof seated in the openings of the top plate and the flange of each element having its tip extending underneath the adjacent boss to anchor said element to said plate; a bottom pair of friction elements having base flanges at their bottom ends seated in the openings of the bottom plate and the flange of each element having its tip extending underneath the adjacent boss to anchor said element to said plate, said top and bottom elements having lengthwise frictional engagement with each other; and springs bearing at their top and bottom ends on said top and bottom spring plates and on the flanges of the top and bottom friction elements.

STACY B. HASELTINE.
